SIGNALING APPARATUS

Joseph A. Hassan, Quincy, Mass., assignor of one-half to William F. McIntyre, Quincy, Mass.

Application January 6, 1938, Serial No. 183,673

3 Claims. (Cl. 250—2)

This invention relates to electrical signaling apparatus, and is especially adapted to signal persons who are beyond hearing distance of the usual voice-transmitted radio message.

5 The principal purpose of my invention is to provide electrical apparatus which is selectively responsive to relatively low audio frequency oscillations emanating from a radio receiving set or other source of amplified audio frequencies, and 10 which causes automatic and sustained actuation of a signal when energized by such low frequency currents. More specifically, the invention contemplates the provision of a vibratory relay which is energized by audio frequency currents, and 15 15 and an electric circuit from said relay to a current source for the signal, said circuit comprising adjustable vibratory contacts for transmitting only extremely low audio frequencies and a time relay for holding the signal in operation while 20 such low frequencies are being transmitted to the current circuit of the signal.

Another object is to construct said apparatus so that its parts are simple and inexpensive to manufacture and assemble, and to provide such 25 a simple and efficient manner of operation of said apparatus that it can be relied upon to function practically perfect over a long period of frequent use.

The foregoing and other objects which will 30 appear as the nature of the invention is better understood, may be accomplished by a construction, combination and operative arrangement of parts such as is disclosed by the drawings and specification. The nature of the invention is 35 such as to render it susceptible to various changes and modifications, and, therefore, I am not to be limited to said disclosure; but am entitled to all such changes therefrom as fall within the scope of my claims.

40 In the drawings:

Figure 1 is a front elevational view of my apparatus in diagrammatic form.

Figure 2 is a diagrammatic view of the electric circuits and devices of my apparatus.

45 As illustrated, the apparatus comprises a radio receiving set R of any well known and suitable make for long or short waves, having a well known type of audio frequency output transformer 12. 50 A wire 13 extends from said transformer 12 to a switch 16 and another wire 15 extends to a voice coil 14 customarily used in radios. The electrical circuit for the radio receiver R usually established through the said voice coil 14 may be 55 opened by manual movement of said movable

switch 16 installed at a point between wiring 13 and 15. Another wire 17 extends from said switch 16 to a coil 20, which constitutes a vibratory relay responsive to the audio frequency currents in the output circuit of the radio receiver 5 and another wire 18 extends from said coil 20 to said transformer 12. Said switch 16 is shown in a neutral position in Figure 1 of the drawings, and in an automobile it ordinarily would be mounted on the dash board. The usual radio 10 circuit through said voice coil 14 would ordinarily be kept closed by said switch when the operator is in said auto; but said circuit would be thrown open when the operator steps out of the auto. 15

Said switch 16 is adapted to be moved so that it will establish a circuit to the vibratory relay 20 and thence through my signaling apparatus instead of to said voice coil 14, and thereby illuminate a signal light when a signal is broadcasted from headquarters.

It is desirable that my signaling apparatus respond to sound waves of a different frequency than those ordinarily caused by the human voice, and they preferably should be of lower frequency. 25 I have found that sound waves such as are caused by an ordinary automobile horn or a buzzer are suitable to actuate my signaling apparatus. For this purpose I provide the vibratory relay 20 capable of mechanical movement when actuated 30 by impulses from sound waves. It has a spider 21 and a coiled retainer spring 22, as shown. The ordinary voice coil for a loud speaker, but without the cone, will serve as said coil 20, or any device that sufficiently moves when electrical impulses resulting from sound waves, 35 preferably of low frequency, strike it. Said coil 20 has a magnetic field 24, one of the permanent magnetic type being desirable, so that wires 35 establishing a circuit from said coil 20 to a battery 30 B or other source of electrical power may be dispensed with. Resting on said coil 20, or so positioned as to be immediately responsive to any movement of said coil 20, is a lever L, pivotally connected as at 25 to a support 25a, which lever consists of a main bar 26 having an extension member 27 at the front thereof, on the end of which is a contact point 28 which normally is lower than and spaced from another contact point 29 stationarily mounted opposite thereto. At the rear of said bar 26 is another extension member 31 which serves as counterbalancing means. Both said extension members 27 and 31 are preferably made of spring steel 40

45 50 55

and are light in weight so they will be sensitive and readily moved when the electrical impulses pass through said coil 20. A wire 33 extends from said lever L to the positive side of the 5 battery B. A tension spring 35 extends from said lever L to a supporting bracket 36 on which it is adjustably mounted, and serves to normally keep said contact points 28 and 29 in their normal inactive position, spaced from each other. The 10 distance of such spacing should be such that said contact points will contact each other only when electrical impulses of not less than a pre-determined frequency actuate said coil 20. In this instance, the sound waves created by the 15 ordinary human voice in broadcasting messages would not result in the creation of impulses to move said contact points 28 and 29 into contact with each other; but sound waves of lower frequency would result in movement of said lever 20 L sufficiently to establish said contact and thereby close the circuit as described. It will be observed that the spacing of the contacts 28 and 29 may be readily adjusted by varying the 25 position of the contact 29 or by regulating the tension of the spring 35 (Fig. 1), so that the impulses transmitted through the circuit including wires 33 and 40 may be regulated according to the value of the audio frequencies which are desired to be effective in actuating the signal 30 light, as hereafter described.

A wire 40 connects said upper contact point 29 to an electrical relay 41, such as is commonly known, which relay has a movable core 42 and a retainer spring 43. A wire 44 connects said 35 relay to the negative portion of battery B.

An arm 46 is connected to said relay 41 so as to move with said core 42, being pivotally mounted as at 47 to a fixed support 48, and being connected as at 49 to a knife switch blade 50 of a 40 knife switch 51, so that movement of said relay core 42 moves said arm 46 to thereby cause said blade 50 to move vertically into and out of engagement with and between two contact spring members 52 forming part of said knife switch 51. 45 A tension spring 53 normally keeps said blade 50 spaced from said spring contact members 52. A wire 54 extends from said switch blade 50 to the minus part of said battery B, while another wire 55 extends from one of said switch spring members to an electric light 57 and more particularly to the filament, from which another wire 58 extends to the positive side of said battery B.

Ordinarily messages from headquarters, such as are transmitted from a police broadcasting station, are received through the radio receiving set R in the usual manner when the switch 16 is in such a position that an electrical circuit between said transformer 12 and said voice coil 14 is established. When, however, a police officer or 55 other person is not within hearing range of said radio messages; but said signal light 57 is visible to him, and there is a message for him, in order to attract his attention a signal or signals are given by lighting said light 57, such as lighting 60 it three times intermittently, by means of my signaling apparatus, the officer having thrown the switch 16 which opens the usual radio circuit and closes the circuit to said coil 20, before 65 leaving the radio set R. To so signal a person a sound is transmitted which causes low frequency 70 sound waves of sufficient energy to actuate said coil 20 which in turn moves said lever L and thus moves said contact point 28 into contact with said point 29, whereupon a circuit is established to said relay and the impulses are trans-

mitted therethrough to said relay core 42 which is thereby moved, whereby said arm 46 raises said knife blade 50 into engagement between and with said spring members 52 to close a circuit, and thereby illuminate said signal light 57, or if the signal is a buzzing device, which it could be, the closing of said circuit would sound it. If the person for whom headquarters has a message answers to a signal consisting of three intermittent illuminations of said light, the broadcaster 10 would sound the device causing low frequency sound waves three distinct times, and each time the contact points 28 and 29 would contact each other, and likewise the knife switch blade 50 would contact the spring contact members 52 to 15 close said knife switch 51, to thereby illuminate the signal light three times. Of course, when the person at headquarters ceases to sound the device, said contact points 28 and 29 immediately 20 separate and said blade 50 falls below said spring contact members 52 to its normal position away from them, with the result that the circuit is immediately opened and illumination of the signal light ceases, as the circuit depends upon the low frequency sound waves to maintain its 25 continuity. Upon the return of the person to the auto or other place where the radio receiver was located, he would move said switch 16 and thereby close the usual radio circuit and listen to the message broadcasted to him from headquarters. 30 The circuit leading to the radio receiver from the battery B is completed by wire 60 and wire 61 to the positive and negative parts of said battery, respectively.

The energy or electrical impulses coming 35 through said transformer 12, which are created by the low frequency sound waves, is sufficient, in my apparatus, to actuate said magnetic coil 20 and thereby move said lever and move said contact points 28 and 29 into contact with each 40 other; but this energy is insufficient to cause a movement that brings said switch blade 50 into contact with said spring members 52, consequently this latter movement must depend upon the completion of a circuit to a definite source of 45 electrical supply, such as a battery B.

It will be apparent from the foregoing that the output transformer 12 (herein illustrated and described as an element of the output circuit of a radio receiving set) which supplies audio frequency oscillations to the vibratory relay 20, may form part of any suitable amplifying output circuit such as that of a public address system as well as that of a radio receiver; and that the essence of this invention resides in the provision of means, such as the adjustable contacts 28 and 29 for selectively energizing the signaling circuit only when the relay 20 is receiving relatively low audio frequency oscillations which cause a greater movement of the moving coil of 60 the relay than do audio frequencies of higher value—in combination with a time relay for holding the signal in operation while such low frequencies are passing through vibratory relay 20. It is also evident that the signal (herein 65 described and illustrated as the light 57) may be a bell, buzzer, or movable signaling element, as well as an electric lamp.

What I claim is:

1. Electrical signaling apparatus, comprising a 70 radio receiver, an output transformer associated therewith for producing amplified audio frequency oscillations, a voice coil, a transmitting circuit including the transformer and voice coil, a vibratory relay having a movable core, a sig- 75

naling circuit associated with said transformer and relay, and a manually operable, double-contact switch selectively operative to close either of said circuits respectively for operating the transmitting circuit or the signaling circuit, the signaling circuit also comprising a signal and a circuit therefor including a current source and a switch, a time relay and a circuit therefor including a current source and a pair of normally spaced contacts disposed in operative relation to said vibratory relay, one of said contacts being movable and being engaged by the movable core of the vibratory relay during energization thereof and said contacts being so spaced that they are closed only by extreme movement of said core in response to relatively low audio frequencies thereby to actuate the time relay, and said switch being operatively connected to the movable core of the time relay so that the switch is closed while said relay is energized, thereby to actuate the signal.

2. Electrical signaling apparatus, comprising a radio receiver, an output transformer associated therewith for producing amplified audio frequency oscillations, a voice coil, a transmitting circuit including the transformer and voice coil, a vibratory relay having a movable core, a signaling circuit associated with said transformer and relay, and a manually operable, double-contact switch selectively operative to close either of said circuits respectively for operating the transmitting circuit or the signaling circuit, the signaling circuit also comprising a signal and a circuit therefor including a current source and a switch, a time relay and a circuit therefor including a current source and a pair of normally spaced contacts disposed in operative relation

to said vibratory relay, a pivoted lever carrying one of said contacts and disposed in the path of movement of the core of the vibratory relay so that the contact on the lever is moved toward the other contact when said relay is energized, a spring connected to the lever and tending to hold said contacts apart, said contacts being so spaced that they are closed only by such movement of said core as is sufficient to overcome the resistance of said spring and as is caused by relatively low audio frequencies, thereby to energize the time relay, and said signal switch being operatively connected to a movable element of the time relay so that the switch is closed and held closed while said relay is energized, thereby to actuate the signal.

3. Electrical signaling apparatus, comprising a radio receiver, an output transformer associated therewith for producing amplified audio frequency oscillations, a voice coil, a vibratory relay having a movable core, a signaling circuit associated with said transformer and relay, and a manually operable, double-contact switch selectively operative to close either of said circuits respectively for operating the transmitting circuit or the signaling circuit, the signaling circuit also comprising a signal and a circuit therefor including a current source and a pair of normally spaced contacts disposed in operative relationship to said relay, one of said contacts being movable and being engaged by the movable core of the relay during energization thereof, and said contacts being so spaced that they are closed only by extreme movement of said core in response to relatively low audio frequencies, thereby to actuate the signal.

JOSEPH A. HASSAN.
